PUMP JACK

Roy W. Wagner, Fairbury, Nebr.

Application June 5, 1945, Serial No. 597,636

2 Claims. (Cl. 60—52)

1

The present invention relates to new and useful improvements in pumps for wells, and more particularly to a pump jack for water wells.

An important object of the present invention is to provide a hydraulic pump jack of this character embodying a closed fluid system in which a motor-driven gear pump is connected for subjecting a piston to fluid pressure for raising a pump rod connected to the piston, the piston having a valve therein by means of which the fluid in the pump jack is by-passed through the piston during the lowering movement thereof.

A further object of the invention is to provide a pump jack of this character embodying means for connecting with a windmill for the operation of the pump rod when the motor-driven fluid pump is not in use.

A further object of the invention is to provide an apparatus of this character of simple and practical construction, which is efficient and reliable in operation, relatively inexpensive to manufacture and install in operative position to a pump rod, and which otherwise is well adapted for the purposes for which the same is intended.

Other objects and advantages reside in the details of construction and operation, as more fully hereinafter described and claimed, reference being had to the accompanying drawings forming part hereof, wherein like numerals refer to like parts throughout, and in which:

Figure 1 is a vertical sectional view of the fluid motor with parts shown in elevation.

Figure 2 is a top plan view with parts broken away and shown in section.

Figure 3 is a sectional view taken substantially on a line 3—3 of Figure 1.

Figure 4 is a vertical sectional view taken substantially on a line 4—4 of Figure 1.

Figure 5 is a transverse sectional view taken substantially on a line 5—5 of Figure 1.

Figure 6 is a transverse sectional view taken on a line 6—6 of Figure 4.

Figure 7 is a vertical sectional view of the piston shown in its raised position.

Referring now to the drawings in detail, wherein for the purpose of illustration I have disclosed a preferred embodiment of the invention, the numeral 5 designates a yoke formed of a pair of spaced parallel vertical rods 6 connected at their ends by cross bars 7 and 8, the upper cross bar 7 having the lower end of a rod 9 attached thereto, while the lower cross bar 8 has the upper end of a pump rod 10 attached thereto.

A motor cylinder 11 is positioned between the rods 6 of the yoke, the cylinder having guides 12

projecting outwardly at opposite sides thereof for slidably receiving the rods. The cylinder 11 is formed on the upper end of an upstanding support 13 adapted for attaching to the upper end of a conventional form of pump barrel 14 by set screws or the like 15. The support 13 is formed with vertically extending slots 16 in which the lower cross bar 8 works and the upper section of the pump rod 10 is slidably mounted in a packing gland 17 in the bottom of the supporting member 13.

A valved piston 18 is mounted for working movement in the cylinder 11, the piston or plunger 18 having a packing 19 at its lower portion and the upper portion of the piston or plunger above the packing is spaced from the walls of the cylinder, as indicated in Figures 1 and 7 of the drawings, to provide a fluid passage therebetween.

A lateral passage 20 is formed in the piston 20 above the packing 19 communicating with a longitudinal passage 21 extending through the bottom of the piston and adapted to be closed by a valve 22 having a stem 23 extending vertically in the piston and slidably mounted therein.

To the upper end of the valve stem 23 is attached a U-shaped trip 24 working in a transverse passage 25 in the upper portion of the piston.

A rod 26 is attached at its lower end to the piston 18 and extends upwardly through the cylinder for attaching to the upper cross bar 7.

A spring-influenced bumper plate 27 is attached in the top of the cylinder 11 in the path of the upper end of the trip 24 during upward movement of the latter for striking the bumper to move the valve 22 downwardly into its open position.

The valve stem 23 is formed with an annular groove 28 in which spring-projected balls 29 carried by the piston are adapted to seat to releasably secure the valve 23 in its downward open position.

A cylindrical chamber 30 is formed at one side of the cylinder 11, the chamber and cylinder having communication at their upper ends by way of a passage 31 and the bottom of the chamber 30 is closed and provided with a passage 32 leading to the intake side of a gear pump 33 of conventional construction. The pump 33 is secured to one side of the support 13 and includes a shaft 34 driven in any suitable manner from an electric motor 35 attached to the lower side of the chamber 30.

A passage 36 connects the outlet side of the pump 33 to the bottom of the cylinder 11 under the piston 18. The passages 32 and 36 are also connected to each other by means of a by-pass

passage 37 having a manually operable valve 38 therein and by means of which fluid is adapted to pass directly from the lower portion of the chamber 30 to the lower portion of the cylinder 11 when the pump 33 is not in operation.

In the operation of the device, the lower section of the pump rod 10 is attached to the well pump and the valve 38 is closed and the motor 35 operated, whereby the pump 33 will force liquid from the chamber 30 into the bottom of the cylinder 11 and thus force the piston or plunger 18 upwardly to raise the pump rod 10.

When the piston or plunger 18 reaches its upper position, the trip 24 will strike the bumper 27, whereby to force the valve 22 downwardly into its open position where it is held in its open position by the spring-projected balls 29 engaging the groove 28 of the stem of the valve. The weight of the pump rod, yoke 5 and piston 18 will then lower the pump rod, the liquid in the cylinder 11 being by-passed through the passages 20 and 21 in the piston around the piston so as not to interfere with the lowering movement thereof. When the valve 22 engages the bottom of the cylinder 11, the valve will be closed and fluid pressure entering the lower portion of the cylinder through the passage 36 will then again raise the piston and the operation will continue.

A windmill (not shown) may be attached to the upper section of the rod 9 for operating the pump of the well when the motor 35 is not in use and the valve 38 is then opened so as to provide for the free passage of liquid from the lower portion of the chamber 30 through the by-pass passage 37 into the cylinder 11, so that the piston 18 may work freely in the cylinder.

A light weight oil is preferably provided in the cylinder 11 and chamber 30 for operating the piston 18 and a passage 39 is provided in the gear pump 33 leading to a bearing assembly 40 for the shaft 34 for utilizing the oil for lubricating the shaft.

It is believed the details of construction, manner of operation and advantages of the device will be readily understood from the foregoing without further detailed explanation.

While I have shown and described a preferred embodiment of my invention, it will be understood that minor changes in construction and arrangement of parts may be made without departing from the spirit and scope of the invention as claimed.

Having thus described the invention, what I claim is:

1. In a pump jack, the combination, which comprises, a motor cylinder fixedly mounted on a well casing, a double end yoke associated with said motor cylinder, a pump rod extending into the well casing from the lower end of the yoke, and a piston rod extending into the motor cylinder from the upper end of the yoke; a piston in the said motor cylinder positioned on the end of

said piston rod, a valve having a stem longitudinally positioned and slidable in said piston, contact fingers extending from the end of said valve stem positioned on opposite sides of said piston rod, said piston having a valve seat associated with said valve, said valve extending beyond the end of the piston and positioned for contact with the end of the motor cylinder wherein contact of the valve with the inner surface of the end of the cylinder closes the valve, said piston having a passage extending therethrough associated with the valve and adapted to be closed thereby, said fingers of the valve stem positioned to actuate the said valve to open position upon engagement thereof with an obstruction in the opposite end of the cylinder and means resiliently holding said valve in the open position.

2. In a pump jack, the combination, which comprises, a motor cylinder fixedly mounted on a well casing, a double-end yoke associated with said motor cylinder, a pump rod extending into the well casing from the lower end of the yoke, and a piston rod extending into the motor cylinder from the upper end of the yoke; a piston on the said piston rod positioned in said motor cylinder, a valve having a stem longitudinally positioned and slidable in said piston, contact fingers extending from the end of said valve stem positioned at opposite sides of said piston rod, said piston having a valve seat associated with said valve, said valve extending beyond the end of the piston and positioned for contact with the end of the motor cylinder wherein contact of the valve with the inner surface of the end of the cylinder closes the valve, said piston having a passage extending therethrough associated with the valve and adapted to be closed thereby, said fingers of the valve stem positioned to actuate the said valve to open position upon engagement thereof with an obstruction at the opposite end of the cylinder, means resiliently holding said valve in the open position, a complementary bypass cylinder positioned parallel to said motor cylinder, and means connecting said bypass cylinder to said motor cylinder for freedom of travel of said piston.

ROY W. WAGNER.
